UNITED STATES PATENT OFFICE.

NORMAN SHUPE, OF LONG BEACH, CALIFORNIA.

GAME APPARATUS.

1,316,513.

Specification of Letters Patent. Patented Sept. 16, 1919.

Application filed November 9, 1918. Serial No. 261,816.

To all whom it may concern:

Be it known that I, NORMAN SHUPE, a citizen of the United States of America, residing at Long Beach, in the county of Los Angeles and State of California, have invented new and useful Improvements in Game Apparatus, of which the following is a specification.

The object of the invention is to improve certain features of the game apparatus covered by Patent #1,242,942, granted October 16, 1917, particularly with reference to the re-setting mechanism for the batting lever and related parts, the means for actuating the closures for the ball delivery or discharge chute and for re-setting the means by which said closure is opened to permit the discharge of the ball, and means for protecting the operator or player and bystanders or spectators.

With these and related objects in view the invention consists in a construction, combination and arrangement of parts herein-after set forth, it being understood that changes in form, proportion and details of arrangement may be resorted to within the scope of the appended claims without departing from the spirit of the invention.

In the drawing:

Figure 1 is a general side view of the apparatus showing the ball-way or tunnel and terminal station respectively provided for the player and the mechanism by which the ball is returned after a specified operation by the player.

Fig. 2 is a vertical sectional view of the casing in which the operating mechanism is inclosed, and indicating such mechanism in full and dotted lines respectively in the set position and in the sprung or operated position.

Fig. 3 is a rear elevation partly broken away to show more clearly the re-setting devices.

Fig. 4 is a detail view partly in section showing the yielding closure member for the ball delivery chute.

Inasmuch as in general features the present apparatus corresponds with that disclosed in patent above noted, it will be sufficient for the purposes hereof to refer only in brief terms to the parts which remain unchanged by explaining that the ball-way or tunnel consists of longitudinal frame bars arranged convergently from the operating station indicated at 11 to the target or

mechanism station 12, said frame bars being supported by suitable standards 13, and said frame work being adapted to support a covering 14 of canvas or similar material which with the upper frame elements 15 should be extended forwardly and inclined downwardly to form a canopy terminating in a vertical back-stop or screen 16, designed to protect the player and bystanders or spectators.

Within the casing 17 at the target end of the apparatus is arranged a batting lever 18 fulcrumed as at 19 to a suitable interior frame member and having connected to its lower end an actuating spring 19' adjustable by means of a rod 20 which preferably extends through the rear wall of the casing and is fitted with an adjusting nut 21, whereby the tension of the spring may be varied from the outside, or without opening the casing. The batting lever is provided at its upper end with a yielding blade 22 adapted for adjustment as to inclination to vary the direction of projection of a ball 23 arranged in the path thereof and normally seated in a ball delivery chute 24 having at its outlet a yielding closure 25 which is hinged as at 26 and is adapted to be opened to permit of the passage of the ball. Said closure is normally and yieldingly held closed as by springs 27 and is adapted to be opened by means of a follower 28 carrying pivotal fingers 29. An advance movement of the follower causes the tail portion 30 of the finger to engage a stop 31, and thereby swing the longer arm of said finger in a direction which serves to open the chute door or closure with the least possible frictional resistance. This follower is actuated by means of a coiled spring 32 having a tension adjusting means consisting of a rod 33 and an engaging nut 34.

The forward or active operation of the follower is controlled by the batting lever through the agency of a trip lever 35 pivoted at an intermediate point as shown at 36 having its lower end connected as at 37 to the batting lever and having its upper end connected as at 38 to the follower. Hence as the batting lever advances to strike and project the ball the trip lever is actuated to advance the follower and open the closure so as to open the way for the discharge of the ball while the tension of the spring 32 assists in actuating the follower and at the same time the trip lever when the batting lever is released from its set position as

shown in full lines in Fig. 2. For maintaining said batting lever in the set position a trigger bar 39 is pivotally mounted as at 40 and is provided with a shoulder 41 to engage 5 a pin 42 on the batting lever, and for tripping the trigger to release the batting lever there is employed a trip arm 43 pivoted at 44 and having an anti-friction roll 45 resting under the trigger and yieldingly held in 10 its normal position by the spring 51.

The target 47 which may be of any preferred construction is provided with a bull's-eye plate 48 movably mounted for reversion when properly struck by a thrown ball, and 15 connected with said bull's-eye member is a stem 49 attached at its rear end to the trip arm 43, so that the reversion of the bull's-eye member serves to actuate the trip arm and hence displace the trigger and release 20 the batting arm so that the latter may cause the desired projection of the ball from the chute, which is at the same time opened for the escape of the ball by the means hereinbefore described. A buffer 50 is arranged in 25 the path of the batting lever and is yieldingly supported by a spring 51.

For the return of the batting lever to its normal position there is employed a re-setting lever 52, located at the front end or 30 operating station of the tunnel within convenient reach of the player and connected by a draw rod 53 with a flexible runner 54 which traverses grooved pulleys 55 and 56 and is terminally attached to the trip bar as at 57. 35 Thus after the release of the batting lever by the tripping of the trigger, and the accompanying discharge of the ball which may be caught by the player, it is only necessary to operate the hand lever 52 by drawing it forward to cause the batting lever to be returned and locked in its set or operative position for subsequent release as explained.

In practice it is preferable to use a duplicate actuating spring 19^a for the batting 45 lever or element, the same being connected with the lever for example at or near the point of connection of the latter with the lower arm of the trip bar as shown at 58, a tension rod 59 being connected with said 50 spring and having an adjusting nut 60. Also as a means for neutralizing the restraining effect of the runner 54 upon the trip bar a counter-balance 61 may be connected therewith by a cable 62 extending over 55 a direction pulley 63. Also the connection

57 between the runner and the trip lever may consist of a clamp as shown, the position of which on the lever may be varied to change the leverage, the clamp being held in its adjusted positions by a set screw 64.

The above indicated changes in the construction and arrangement of the parts of the game apparatus tend to increase the efficiency and at the same time the durability of the device by eliminating unnecessary parts 65 and hence avoidable friction, and consequently the necessity for readjustment, even after hard and protracted usage, is minimized.

What is claimed is:—

1. In an apparatus of the class described the combination of a pivotal spring actuated batting lever and locking and trip mechanisms for controlling the same, a ball chute traversed by the free end of the batting lever 75 for discharging a ball therefrom, a closure for said chute yieldingly held in its chute closing position, a follower carrying a tilting closure actuating finger, and connections between the batting lever and the follower. 80

2. In an apparatus of the class described the combination of a pivotal spring actuated batting lever and locking and trip mechanisms for controlling the same, a ball chute traversed by the free end of the batting 85 lever and having a closure yieldingly held in its closed position, a follower operatively connected with the batting lever, and a closure operating finger tiltably mounted upon the follower for engagement with the 90 closure when the batting lever is released to traverse the chute.

3. In an apparatus of the class described the combination of a pivotal spring actuated batting lever and locking and trip mechanisms for controlling the same, a ball chute traversed by the free end of the batting lever and provided with a closure yieldingly held in its chute closing position, a follower 100 operatively connected with the batting lever and a trip finger pivotally mounted upon said follower and having a tail portion for engagement with a fixed shoulder to cause swinging movement of said finger as the follower is advanced, the free end of said 105 finger being adapted for engagement with the chute closure for moving the same in opposition to its yielding closing means.

In testimony whereof I affix my signature.
NORMAN SHUPE.
